HEDDLE FRAME FOR LOOMS

Emil Streuli, Horgen, Switzerland, assignor to
Grob & Co., A. G., Horgen, Switzerland

Application May 18, 1942, Serial No. 443,449

6 Claims. (Cl. 139—92)

The present invention relates to heddle frames for looms, and more particularly to improved means for connecting the heddle frame with the shedding device of the loom.

The main object of the invention consists in the provision of connecting means or clutches adapted to hold the heddle frame in its proper position and preventing movement and lateral displacement of the heddle frame in respect to the members of the shedding mechanism operating the heddle frame.

A further object of the invention is to provide improved connecting means which may be fastened to the heddle frame but which may be readily released to permit the adjustment or the removal of the heddle frame.

A further object of the invention consists in a heddle frame support which will automatically lock the heddle frame while the shedding is in operation.

A further object of the invention is to provide a heddle frame support which will be simple and inexpensive in construction yet sturdy and reliable in operation. Other objects will appear from the specification and claims.

The nature and characteristic features of the invention will be more readily understood from the following description taken in connection with the accompanying drawing forming part thereof, in which

Fig. 1 is a side elevation view of a heddle frame, parts being broken away.

Fig. 2 shows in a side view a self-locking hook attached to the upper rail of the heddle frame the same being drawn to an enlarged scale.

Fig. 3 is a front view thereof.

Fig. 4 is a section taken on line IV—IV of Fig. 2.

Fig. 5 shows in a side view a self-locking hook attached to the lower bar of the heddle frame.

Fig. 6 is a front view thereof.

Fig. 7 shows in a side elevation and

Fig. 8 in a front view a modified construction of a suspension hook with means to secure same on a rail of the heddle frame.

Figs. 9 and 10 are each an enlarged fragmentary side elevation view illustrating a supporting hook in conjunction with a portion of a rail of the heddle frame on which they are mounted.

It will, of course, be understood that the description and drawing herein contained are illustrative merely and that various modifications and changes may be made in the structure disclosed without departing from the spirit of the invention.

Referring to the drawing, the heddle frame there shown comprises a top and a bottom rail 9, 9 interconnected at their ends by bars 40. The rails or staves 9, 9 consist of light metal for instance of an aluminum alloy, they are hollow and are provided with ribs 7. The ribs 7, are of T-shape in cross section each rib has its head or lateral flanges extending from the stem 8 so that supporting attachments or clutches 1 may be mounted thereon in such a manner that they are free to slide longitudinally over the said flanges. For the suspension of the heddle frame the clutches 1 embrace the rib 7 of the rail 9. The clutch 1 shown in Figs. 2, 3 and 4 comprises 15 two like members 4, 5 held together by a rivet 3. Each member 4, 5 is provided with a jaw 6 centrally spaced from the web, but having two extensions 41, 41¹ engaging the stem or web 8 of the rib 7. On the rivet 3 a hook 12 is rotatably 20 mounted. The hook 12 has two bevelled cam faces 42 engaging correspondingly bevelled cam portions 10, 11 of the upper parts 13, 14 of the members 4, 5. By turning the hook 12 to its upright position shown in Figs. 2 and 3, the parts 25 10, 11 are forced apart the hook acting as a wedge. At the same time the jaw extensions 41, 41¹ are firmly pressed on to the rib 7, the rivet 3 allowing a certain limited play of the parts 4, 5. The clutch 1 is thereby securely held on the 30 heddle frame. The hook 12 is connected by a suitable link, chain or the like, to the shedding mechanism of the loom as known per se.

In Figs. 5 and 6 a clutch is shown for use in conjunction with the bottom rail or stave 9 of 35 the heddle frame when the latter is positively drawn downwards by the shedding motion. The clutch comprises two like members 4¹, 5¹ held by a rivet 3¹ in such a manner that they have some play thereon. On the rivet 3¹ a hook 22 is rotatably mounted having outer cam faces 23 engaging correspondingly shaped cam faces 10¹, 11¹ on the parts 10¹, 11¹ of the clutch. The members 4¹, 5¹ are provided each with a jaw 6¹ engaging the stem or web 8 of the rib 7. When turning 45 the hook 22 into the position shown in Fig. 5 the parts 10¹, 11¹ are forced apart and the extensions 41, 41¹ are firmly pressed on the rib, the hook 22 acting in the manner of a wedge. The hook 22 is connected by links, chains or any 50 other known means with the heddle shaft operating devices of the loom. The heddle assembly cannot accidentally shift when the clutches are firmly held in their place. The clutches may be easily brought in position and are automatically fastened on the rails 9 by the draft exerted on

the hooks 12, 22, when the shedding is started. In Figs. 7 and 8 a modified construction is shown. The clutch comprises two like side parts 31, 32 welded together to form a hook 30 at the upper end and shanks with jaws 6 at the lower end, the latter being centrally spaced from web 8 but being provided with extensions 41, 41¹, engaging the web 8 of the rib 7. Between the shanks of the parts 31, 32 a bolt 34 is rotatably mounted. On said bolt 34 a circular disk 33 is eccentrically secured contacting with the upper edge of the rib 7. By turning the bolt 34 in one direction the disk 33 is firmly pressed on to said rib. The clutch is thereby securely held in position on the rail 9, and the heddle frame is maintained in its proper position, as the extensions 40, 41 are forced against the shoulders of the flanges of the rib 7.

As shown in Fig. 9 the clutch may be fastened in its correct position on the stave 9 of the heddle frame 9 by means of a wedge cam 36 having a slanting groove through which the bolt 35 of the clutch passes. By driving the wedge 36 in the one or the other direction, the clutch may be loosened or securely fixed on the stave 9 of the heddle frame.

Fig. 10 shows a fixing device for the clutch on the stave 49 comprising a locking member 39 slidably arranged between two shanks of a clutch hook 51. The upper edge 37 of the rib 57 is toothed and the locking member 39 is provided with teeth 38 engaging the toothed edge 37. A spring 40 acting on the locking member 39 holds the same in engagement with the rib 57, while the loom is being operated.

While I have described my invention in connection with heddle frames having metallic rails, I wish to point out that the invention may be used in combination with heddle frames having wooden staves, the same being provided with iron rail having T-shaped cross section.

To secure a firm grip of the clutches on the faces of the ribs the latter may be roughened or toothed, the jaws of the clutches having forming engaging faces.

What I wish to secure by United States Letters Patent is:

1. An attachment clutch for heddle frames, the staves of which have ribs each with a web and an enlarged head, comprising a pair of interconnected jaws, one on each side of a rib, with elongated portions opposite the web of the rib and centrally spaced from the web, the elongated portions having terminal parts in sliding engagement with the web.

2. An attachment clutch for heddle frames, the staves of which have ribs each with a web and an enlarged head comprising a pair of interconnected jaws, one on each side of a rib the jaws having elongated portions, the central portions of the jaws being spaced from the web and head of the rail, while the elongated portions have terminal parts in sliding engagement with the web and head of the rail and means for forcing the terminal parts into gripping engagement with the web of the rib.

3. An attachment clutch for heddle frames, which have rails, comprising a pair of jaws, one on each side of the rail, a pin traversing the jaws beyond the outer edge of the rail, a cam member rotatable about the axis of the pin and adapted upon rotation to force the inner portions of the jaws into engagement with the rail at selectively determined points lengthwise of the rail, and an attachment hook integral with said rotary cam member.

4. In an attachment clutch for heddle frames having rails each with a rib which consists of a web and an enlarged head, the combination of a hook member, two jaws on said member, one on each side of a rib, and means interposed between the jaws for forcing the jaws laterally against the rib while they are in engagement with the head of the rib at selectively determined points lengthwise of the rail.

5. In an attachment clutch for heddle frames which are provided with rails having ribs each with a web and an enlarged head, the combination of a hook member, two jaws associated with said hook member, one on each side of a rib, means interposed between the jaws for locking the jaws laterally against the web of the rib in parallel planes and against the head of the rib in a plane angularly related to the first named plane at selectively determined points lengthwise of the rail.

6. In an attachment clutch for heddle frames, the staves of which are provided with ribs each with a web and an enlarged head, the combination of an attachment hook, two jaws connected to the hook, one on each side of a rib, and means interposed between the jaws and in permanent engagement with the inner faces thereof for forcing the jaws against the web of the rib while they are in engagement with the head of the rib at selectively determined points lengthwise of the rail.

EMIL STREULLI.
